SKI CLAMP

Matts Djøs, Seattle, Wash.

Application December 1, 1948, Serial No. 62,875

3 Claims. (Cl. 280—11.37)

1

My invention relates to the art of ski clamps. More particularly my invention relates to a ski clamp which holds a pair of skis in juxtaposed position while being carried or stored.

Skis are difficult and awkward members to carry, particularly when not held together, and also when not properly held together.

Moreover, skis have their running surfaces coated with wax, which surfaces need protection. This surface is damaged by rubbing or direct contact between the skis. The ski clamps which have been heretofore provided are of a complex character involving the tightening or loosening of screws to apply or remove the clamps. Also, such prior art ski clamps are of a character which are difficult to carry in one's pocket while the skis are in use. Moreover, skis are provided with a definite shape and curvature and any means employed for securing them together must be such as to be free of imposing stress or strains on the skis. Clamps which permit contact between the running surfaces of two skis cause injury to such surfaces and to wax thereon. Also, if clamps employing straps are used, such straps when they have collected snow and ice become most difficult to handle.

A primary object of my invention is to overcome these various objections and difficulties of prior art ski clamps. Further primary objects of my invention are to provide a ski clamp characterized by its simplicity to manufacture and use, smallness of size, lightness of weight, and characteristics, so that it can be readily carried in one's pocket while skiing and ready for use when the skis are removed from the feet.

Also, it is a primary object of my invention to provide a clamp which is free of stress and strain on the skis when the clamp is applied thereto, and thereby provide for keeping the skis in their desired predetermined shape.

Also, it is an object of my invention to provide ski clamps which eliminates bothersome removal of toe straps before and after skiing, and free of screws or bolts which may become lost or damaged or rusted, and which may be readily and conveniently applied to the skis, and maintain them in separated position yet firmly held.

Also, it is an object of my invention to provide such a clamp of economical construction.

The above mentioned general objects of my invention, together with others inherent in the same, are attained by the device illustrated in the following drawings, the same being a preferred form of embodiment of my invention, throughout

2

which drawings like reference numerals indicate like parts:

Figure 1 is a view in side elevation showing a pair of skis clamped together by clamps of my invention;

Fig. 2 is a plan view of the devices shown in Fig. 1;

Fig. 3 is a sectional view, with parts in elevation, taken substantially on broken line 3—3 of Fig. 1 and on a larger scale than Fig. 1; and

Fig. 4 is a fragmentary plan view and substantially on the same scale as Fig. 3.

The skis 5 and 6 to be held by the clamps of my invention may be of various sizes and shapes, and those illustrated in the drawings are one common style on the market.

The ski clamps of my invention are numbered generally 7 in Figs. 1 and 2 of the drawings, and the respective parts thereof are numbered specifically in the larger views—Figs. 3 and 4.

Each of the brackets 7 has a sinuous curved form in side elevation and each bracket comprises valleys or ski receiving recesses 8 separated by curved or spacer portions 9. The valley portions 8 terminate in leg portions 10, 11, 12 and 13. The leg portions 10, 11 and 12 may be similar in shape, and each thereof is connected with an end portion of one of the springs 15. This may be accomplished by providing each of said leg portions 10, 11 and 12 with an opening 14 through which is threaded an eye of a spring 15. The leg portion 13 carries a hook-like portion 16. A latch 17 is provided with an opening 18 to receive therethrough the hook-like portion 16. Preferably, an opening 19 is provided in the latch 17 so that one's fingers do not tend to slide after grasping said latch 17. Obviously, other expedients may be employed for the opening 19 as knurled surfaces, raised portions, etc., to accomplish the same purpose.

While I have shown valleys 8, each of which receives therein a side portion of a ski and spacer curves 9, it is to be expressly understood that my invention is not limited to a uniform sinuous curved clamp, and valleys which interfit with the skis and other shaped spacer members may be employed. However, a sinuous curved clamp lends itself to high speed stamping processes and is preferable.

Also preferably, each of the valleys 8 is preferably provided with a reinforcing rib 20 which may be stamped at the time of forming the valleys 8. If it is desired to have the valleys 8 snugly fit the edges of skis or to make the device 55 adaptable for use over a large range of different

thicknesses of skis, the brackets 7 may be formed of spring steel. Also, the hook-like portion 16 is preferably arcuate in section for reinforcing purposes as appears from comparing the elevational view thereof in Fig. 3 and the plan thereof in Fig. 4.

The inwardly bent portions 9 function to space and securely hold the skis 5 and 6 so they may be handled as a unit.

The tension means, which are illustrated and described as springs 15 but not limited thereto, are of a length and strength so they can be readily applied or removed, and, at the same time, will have sufficient spring tension to clamp and maintain the skis in the desired juxtaposed position.

In order to apply a clamp to given portions of two spaced skis, the edge portions of the ski 6 are inserted in the two lower valleys 8 of two laterally spaced clamps and the lower spring 15 is somewhat extended. Then the ski 5 is placed in superposed position above the ski 6 and with the edge portions of the ski 5 in the remaining two valleys 8. Then the hook-like portions 16 is held in place and the latch 17 is pulled outwardly putting the upper spring 16 under tension, and the opening 18 of the latch 17 is placed over and engaged with the hook-like portion 16. In order to remove a clamp from a pair of skis, it is only necessary to lift the latch or angularly move the same upwardly and the opening 18 may be disengaged from the hook-like portion 16. While I have shown a pair of clamps 7 employed, obviously a greater number may be employed if desired.

From the foregoing description, it is obvious that I have provided a device which is simple in construction and may be readily secured to or removed from a pair of skis and will hold the same in position so that a pair of skis can be handled as a unit. The device is of a size and nature so that it tends to readily collapse when not in use and can easily be carried in one's pocket to be available when needed.

Obviously, changes may be made in the forms, dimensions, and arrangements of the parts of my invention without departing from the principle thereof, the above setting forth only a preferred form of embodiment.

I claim:

1. A ski clamp comprising a pair of laterally spaced sinuously curved brackets, each bracket having: two spaced valleys for receiving therein an edge portion of ski, an inwardly projecting ski spacing hill between said valleys, and spring engaging means at its end portions, at least one of said spring engaging means being a portion of a detachable catch means; spaced tension

springs for urging said brackets toward each other when skis are between said brackets; and bracket engaging end portions on each of said tension springs, at least one of said bracket engaging spring end portions terminating in the other portion of a detachable catch means which is engageable with the first mentioned portion of said detachable catch means.

2. A ski clamp comprising a pair of laterally spaced sinuously curved brackets, each bracket having: two spaced valleys for receiving therein an edge portion of a ski, an inwardly projecting ski spacing hill between said valleys, and spring engaging means at its end portions, at least one of said spring engaging means being a portion of a hook and hook eye detachable catch means; spaced tension springs for urging said brackets toward each other when skis are between said brackets; and bracket engaging end portions on each of said tension springs, at least one of said bracket engaging spring end portions terminating in the other portion of said hook and hook eye detachable catch means which is engageable with the first mentioned portion thereof.

3. A ski clamp comprising a pair of laterally spaced sinuously curved brackets, each bracket having: two spaced valleys for receiving therein an edge portion of a ski, an inwardly projecting ski spacing hill between said valleys, and spring engaging means at its end portions, at least one of said spring engaging means being the hook portion of a detachable catch means; spaced tension springs for urging said brackets toward each other when skis are between said brackets; and bracket engaging end portions on each of said tension springs, at least one of said bracket engaging spring end portions terminating in the eye hook receiving portion and handle operating means of a detachable catch means which is engageable with the first mentioned portion thereof, said handle operating means being provided with means deterring sliding of one's fingers with respect thereto.
